US00D892348S

(12) **United States Design Patent** (10) Patent No.: **US D892,348 S**
(45) Date of Patent: **** Aug. 4, 2020**

(54) **GENETIC TESTING MACHINE**

(71) Applicant: **KABUSHIKI KAISHA Mirai Genomics**, Yokohama-shi, Kanagawa (JP)

(72) Inventors: **Norihiro Matsuyama**, Kanagawa (JP); **Koya Kurokawa**, Ehime (JP)

(73) Assignee: **KABUSHIKI KAISHA Mirai Genomics**, Kanagawa (JP)

(**) Term: **15 Years**

(21) Appl. No.: **29/663,165**

(22) Filed: **Sep. 12, 2018**

(30) **Foreign Application Priority Data**

Mar. 13, 2018 (JP) 2018-005209

(51) LOC (12) Cl. **24-01**

(57) **CLAIM**

The ornamental design for a genetic testing machine, as shown and described.

DESCRIPTION

FIG. 1 is a front elevational view of a genetic testing machine, showing our new design;

FIG. 2 is a back view thereof;

FIG. 3 is a left side view thereof;

FIG. 4 is a right side view thereof;

FIG. 5 is a top plan view thereof;

FIG. 6 is a bottom plan view thereof;

FIG. 7 is a front and top perspective view thereof;

FIG. 8 is a front and bottom perspective view thereof; and,

FIG. 9 is a back and bottom perspective view thereof.
